US00D697447S

(12) **United States Design Patent**
Kelleghan

(10) **Patent No.:** **US D697,447 S**
(45) **Date of Patent:** **** Jan. 14, 2014**

(54) **BRAIDED BRACELET CLOSURES**

(75) Inventor: **Brian James Kelleghan**, Longmont, CO (US)

(73) Assignee: **Bison Designs, LLC**, Longmont, CO (US)

(**) Term: **14 Years**

(21) Appl. No.: **29/394,324**

(22) Filed: **Jun. 15, 2011**

(51) LOC (10) Cl. **11-01**

(52) U.S. Cl.

USPC **D11/87**

(58) **Field of Classification Search**

USPC D11/1-2, 7, 40-44, 46-49, 53, 56, 57, D11/59-61, 63, 65, 79-83, 86-87, 89-90, D11/91-92, 99, 101, 106, 114-116, D11/200-201; 63/18-20
